UNITED STATES PATENT OFFICE.

DANIEL G. DANIELS, OF NEW YORK, N. Y.

DESIGN FOR A SWIVEL FOR EXERCISERS.

46,629.

Specification for Design. Patented Nov. 10, 1914.

Application filed August 7, 1914. Serial No. 855,701. Term of patent 7 years.

To all whom it may concern:

Be it known that I, DANIEL G. DANIELS, a citizen of the United States, residing at New York, borough of Brooklyn, in the county of Kings and State of New York, have invented a new, original, and ornamental Design for a Swivel for Exercisers, of which the following is a specification, reference being had to the accompanying drawings, forming part thereof, and of which—

Figure 1 is a side elevation of a swivel for

an exerciser; and Fig. 2 is an end elevation thereof of both figures showing my new design.

I claim:

The ornamental design for a swivel for an exerciser, as illustrated.

DANIEL G. DANIELS.
